MEANS FOR AUTOMATICALLY OPERATING
A NUMBER OF ELECTRIC RELAYS OR
SOLENOIDS AT A PRESET TIME

Ivan Andersson, St. Petersburg, Fla.

Application October 15, 1947, Serial No. 780,050

5 Claims. (Cl. 161—1)

1

The present invention relates to means for automatically actuating a number of relays or solenoids for operating radios, signals, announcers and the like at a preset time and is applicable to my invention described and claimed in my patent application filed on August 27, 1947, Serial Number 770,914, patent issued Number 2,488,575.

The objects of this invention are to secure accurate timing for the automatic operation, to provide means for adjusting and setting the clock which controls the automatic operation, and to provide means for automatically changing the automatic operation into manual operation or vice versa.

The accompanying drawings illustrate the invention applied to a radio where:

Fig. 1 is a side view, partly in section and similar to Fig. 5 in my previous application mentioned above, embodying the present invention but with parts omitted which are not essential for the description.

Fig. 2 is a section on line 2—2 of Fig. 1 with cam levers in operative position.

Fig. 3 is a similar view but with cam levers moved into inoperative positions.

Fig. 4 is a fractional view of cam and levers in one position.

Fig. 5 is a fractional view of cam and levers in another position.

Fig. 6 is a fractional view of cam and levers in a third position.

Fig. 7 is a diagrammatic view showing integral parts of the arrangement and the electrical system.

Fig. 8 is a section on line 8—8 of Fig. 7.

Fig. 9 is an end view of a solenoid with armature and latch in inoperative position.

Fig. 10 is a similar view but with armature and latch in operative position.

Fig. 11 shows a fractional plan of a solenoid with connected parts and arrangement for switching on or off a radio to or from the electric supply.

Fig. 12 is an end view of Fig. 11 showing the switch in the on position.

Fig. 13 is a similar view but with switch shown in off position.

As described in my patent application mentioned above, a slotted body 1, Fig. 1, supported on a bracket 23 carries a number of toothed racks 8 having projections 105 which are adapted to engage pins 90 mounted on a rotating disk 13 which also carries contact springs 14 which normally are out of engagement with the contact rings 16, and contact spring 15 which is always in contact with the contact ring 17 which are carried by the non-conducting disk 19, Fig. 1. Any of the pins 90, when struck by a projection 105, causes contact to be established between a correspond-

2

ing contact spring 14 and a contact ring 16. In my previous application this closed an electric circuit through a relay or solenoid, but in the present application a timing device is interposed for more accurate timing. To accomplish this I provide cam 130, Fig. 1, to Fig. 5, mounted on a shaft 131 which is rotated by the clock work 20 and geared to the minute shaft 57 through gear wheels 132, 133 and pinion 112 mounted on said shaft 57, Fig. 1 and Fig. 2. The hour shaft 56 being driven by the same shaft 131 through gearing 132, 133, 134 and gear wheel 117 mounted on the shaft 56, Fig. 1. The cam 130 rotates at the same speed as the minute shaft which is one revolution per hour. The cam has four steps on the periphery equally spaced. Three levers 136, 137 and 138 are mounted so as to be actuated by this cam successively. One lever 136 when actuated by the cam closes an electric circuit through the contact members 139 and 140 which occurs at the end of each quarter hour, Fig. 4, causing an electric solenoid 141, Fig. 8, to be energized, which causes any radio or signal connection to be discontinued. After a short interval a second lever 137 is actuated by the cam 130 which breaks the first said electric circuit through separation of contact members 142 and 143 but closes another electric circuit through contact members 144 and 145, Fig. 2 and Fig. 5, if electric connection has been made between ring 17 and any one ring 16 by the operation of a pin 90 striking a projection 105. By closing the last said electric circuit a solenoid 146 and a solenoid 152 are energized which causes a radio station to be tuned in by push button 200 of a radio 201 being actuated by the armature 155 of solenoid 152. After a further short interval of time a third lever 138 is actuated by the cam 130 which breaks the last said circuit through the separation of contact members 147 and 148, Fig. 2, and Fig. 6, after the radio station has been tuned in, which continue until the first named lever 136 goes into action again.

All the levers are mounted on pivots 149 with one end riding on the cam and the other end which carries a non-conductive stud 150 engaging and operating the contact members. The two contact members 142 and 144 move together by being interconnected through a non-conductive link 151. The solenoids 152 for operating the push buttons have armatures 153 which are held in inoperative positions by helical springs 154 and stops 155 on the reduced ends 156, Fig. 7 and Fig. 9. When a solenoid 152 is energized, the armature is drawn in against the action of the spring 154 and a latch 157 is pushed down by a spring 158, locking the armature in operative position. At the same time the electric current which energizes the solenoid and flows through the contact members 159 and 160 is

broken by the separation of the two contact members, Fig. 10. A rocking shaft 161 carries cams 199 which, when the shaft is rocked in one direction, lifts the latches which frees any armature locked in an operative position, but on rocking it in the other direction, frees the latches and allows any of them to be pushed down and lock the armature in an operative position when a solenoid is energized, Fig. 10.

The shaft 161 is rocked by the operation of the two solenoids 141 and 146, the armatures 162 and 163 of which are connected to a lever 164 rigidly mounted on the rocking shaft 161. The current for energizing the solenoid 141 passes through the contact members 165 and 166 when the armature is in its outward position as indicated in broken lines. The sleeve 167 of non-conductive material carried by the armature 162 holds the two contact members 165 and 166 in contact which allows any incoming current to flow through and energize the solenoid 141 causing the armature to move the sleeve 167 from the contact members separating them and break the circuit. The contact rings 16 are connected by wires 109 to the solenoids 152 through contact members 159 and 160 which are in contact when the armature is in inoperative position, and then by the wires 168 to the electric supply wire 169, Fig. 7. The contact ring 17 is connected by wire 170 to contact member 144 which on the rotation of the cam 130 and passing of a step by the cam lever 137 brings it into contact with contact member 145. When contact has been established between ring 17 with any of the rings 16 by the previous mentioned contact members on the disk 13, Fig. 1, an electric circuit has been closed from supply wire 169, through wire 163, solenoid 152, contact member 160, contact member 159, wire 106, contact ring 16, contact ring 17, wire 170, contact member 144, contact member 145, through wire 171, contact member 148, contact member 147, through wire 172, solenoid 146 and the wire 173 to the electric supply line 174, the result is that the solenoid 146 has been energized and the armature 163 actuated which rocks the shaft 161 and turns the cam 199 which frees the latch 157. The solenoid 152 being in the closed circuit is energized and the armature drawn into an operative position and the latch 157 pressed by the spring 158 into a position which locks the armature in the operative position, causing the contact between the two contact members 159 and 160 to be broken. This condition lasts for fifteen minutes, when a cam step of cam 130 passes the one end of cam lever 138 which brings the two contact members 139 and 140 together closing an electric circuit through the electric supply wire 174, contact members 143 and 142, wire 195, contact member 148 and 139, through wire 175, solenoid 141, contact members 165 and 166, to the electric supply wire 169, the last two contact members being in contact as the armature has been moved to an outward position through lever 164 when solenoid 146 was energized. The solenoid 141 being energized when the last said circuit was established, causes the armature 162 with sleeve 167, of non-conductive material, to be actuated, breaking the contact between 166 and 165, rocking the shaft 161 and cam 199, thereby lifting the latch 157, freeing the armature 154 which is pushed out by the helical spring 153 into an inoperative position, and starting a new cycle of 15 minutes.

To turn on or off the electric supply for the radio following arrangement is made: On the

rocking shaft 161 a disk 176 with a pin 177, Fig. 11, is rigidly mounted and adjacent to this an other disk 178 is loosely mounted. Last said disk carries a handle 179 for manual operation and has a slot 180 through which protrudes the aforesaid pin 177. Two sets of contact members 181 and 182 are provided for connecting the electric supply to a radio or signal system through the wires 183 and 184. The two sets of contacts are actuated by two projections on the loosely mounted disk 178 so that by turning the handle 179 in one direction which is the "on" direction, contact is made between the contact members and the supply circuit through 183 and 184 started. By turning the handle 179 in the opposite direction to the "off" position, the contacts between the contact members 181 and 182 are broken. When the shaft 161 stands in an inoperative position, Fig. 9, the pin 177, Fig. 11, is in a neutral position as shown which will allow the manual handle to be moved into "on" or "off" position without affecting the pin. But if automatic operation is started by one of the pins 96 on disk 13 striking a projection 105 on a rack 8, Fig. 1, and a step of the timing cam 130 passes the end of the cam lever 137, the automatic cycle of 15 minutes as heretofore described will start and the pin 177 on the disk 176 moves in the slot or disk 178 by the rocking shaft 161 provided that the handle 179 stands in the "on" position, Fig. 12. However, does the handle stand in the "off" position, the pin 177 will move into the broken line position, Fig. 13, and the handle 179 will move into the "on" position, closing the contact members 181 and 182 and establish the electric supply circuit for the radio or signals.

If it is desirable to turn off the radio soon after it has been started automatically, the handle 179 is turned to the "off" position. This will turn the pin 177 into the neutral position and rock the shaft 161 and turn the cams 162, lifting the latches 157 out of the way of any armature 154 causing the contact members 159 and 160 to make contact and close a circuit through the solenoid 152 as long as current is flowing, thereby energizing the solenoid and actuate the armature 154 which causes it to chatter when A. C. current is being used, provided that contact still exists between rings 16 and 17 which may last for a few minutes. To prevent this I have arranged two contact members 147 and 148 which are normally kept in contact by the cam lever 138 which is actuated by the cam 130. The contacts form a path in a closed electric circuit but on passing off a step on the cam 130 the lever 138 will allow the contact members to separate and break the circuit which takes place soon after the solenoids 146 and 152 have been energized, thereby allowing the aforesaid manual handle to be turned to the "off" position without producing a chatter.

For setting of the clock the spindle 114 passes through a hole in shaft 21 which carries the clock 20 and is supported by bracket 22. The spindle 114 carries a pinion 113 at one end for engaging pinion 112 mounted on the minute hand shaft 57 and a knurled button 115 at the rear end. A helical spring 116 keeps the pinions out of engagement normally, Fig. 1. A bellcrank 185 is pivoted on a bracket 186, the one arm 187 of which is forked and carries studs which engage a groove 188 in a sleeve 189 rigidly mounted on the spindle 114. The other arm 190 engages a slot 191, Fig. 1 to Fig. 3, in the disk 192 which is loosely mounted on shaft 131. This disk carries three studs 193 adapted to engage the cam levers

136, 137, 138, and turn them away from the cam 130 when the bell crank 185 is turned on its pivot. This occurs when the pinion 113 is pushed into engagement with the pinion 112 for adjustment of the clock enabling the cam 130 to be rotated in both directions freely without interference from the cam levers.

I claim:

1. In an arrangement of an electric coil having an armature for actuating a push button of a radio and forming part of an electric circuit, and means for automatically making and breaking said electric circuit at pre-arranged time intervals, the arrangement of a cam disk provided with steps, means for rotating said cam disk, a cam lever adapted to be actuated by the steps, a set of contact members interposed in the electric circuit and normally open but adapted to be actuated and closed by the cam lever during the aforesaid make and break period, a second cam lever adapted to be actuated a short time after by the cam, a second set of contact members interposed in the electric circuit and normally closed but adapted to be actuated by the last said cam lever and to break the contact a short time after the first said contact members were closed during the make and break period of the pre-arranged time interval, a third cam lever adapted to be actuated by the cam shortly before the first said cam lever is actuated, an electric circuit independent of the first circuit, an electric coil and armature being part of the second circuit, a set of contact members interposed in this circuit adapted to be closed by the said third cam lever before the first cam lever has actuated and closed the first said contact members in the first electric circuit, a second set of contact members interposed in the second circuit and normally closed but arranged to break the second circuit at the same time the first circuit is closed, means for locking the first said armature and push button in an operative position and means adapted to be actuated by the armature and coil in the second circuit for releasing the first said armature and freeing the push button actuated by the said armature.

2. In an arrangement of an electric coil having an armature for actuating a push button of a radio and forming part of an electric circuit, and means for automatically making and breaking said electric circuit at pre-arranged time intervals, a latch for locking the armature in its operative position, means for withdrawing the latch to release the armature, means for withdrawing the armature from its operative position, a second electric coil with an armature interposed in the electric circuit and in series with the first said coil, and means actuated by the second coil and armature for releasing the latch from its inoperative position and allow it to lock the armature of the first said coil in its operative position.

3. In an arrangement of an electric coil having an armature for actuating a push button of a radio and forming part of an electric circuit and means for automatically making and breaking said electric circuit at pre-arranged time intervals, a latch for locking the armature in its operative position, means for withdrawing the latch to release the armature, means for withdrawing the armature from its operative position, a second electric coil with an armature interposed in the electric circuit and in series with the first said coil, means actuated by the second coil and armature for releasing the latch from its inoperative position and allow it to lock the armature of

the first said coil in its operative position, means for connecting said radio to the electric supply of the first said circuit and forming a second circuit, means for making and breaking said circuit, said means being connected to the means actuated by the second coil and armature and operated for actuating the latch.

4. In an arrangement of an electric coil having an armature for actuating a push button of a radio and forming part of an electric circuit and means for automatically making and breaking said electric circuit at pre-arranged time intervals, a latch for locking the armature in its operative position, means for withdrawing the latch to release the armature, means for withdrawing the armature from its operative position, a second electric coil with an armature interposed in the electric circuit and in series with the first said coil, a rocking shaft actuated by the second coil and armature, a cam rigidly mounted on said shaft and arranged for releasing the latch from its inoperative position and allow it to lock the armature of the first said coil in its operative position, means for connecting said radio to the electric supply of the first said circuit and forming a second circuit, contact members interposed in said circuit, means mounted on the aforesaid rocking shaft for actuating aforesaid contact members to make or break the last said circuit.

5. In an arrangement of an electric coil having an armature for actuating a push button of a radio and forming part of an electric circuit and means for automatically making and breaking said electric circuit at pre-arranged time intervals, a latch for locking the armature in its operative position, means for withdrawing the latch to release the armature, means for withdrawing the armature from its operative position, a second electric coil with an armature interposed in the electric circuit and in series with the first said coil, a rocking shaft actuated by the second coil and armature, a cam rigidly mounted on said shaft and arranged for releasing the latch from its inoperative position and allow it to lock the armature of the first said coil in its operative position, means for connecting the said radio to the electric supply of the first said circuit and forming a second electric circuit, contact members interposed in said circuit, a cam loosely mounted on the aforesaid rocking shaft and having a handle for manual operation and a concentric slot, a disk rigidly mounted on the rocking shaft, a pin mounted on said disk and protruding thru the concentric slot in the cam, enabling the cam to be operated manually independent of the disk and rocking shaft, but allowing the pin carried by the disk which is rigidly mounted on the rocking shaft, to automatically engage one of the ends of the concentric slot in the cam and operate the same thereby actuating the contact members to make and break the electric circuit.
